BERT G. DUNHAM, OF ROCHESTER, NEW YORK, ASSIGNOR, BY MESNE ASSIGNMENTS, TO WESTERN ELECTRIC COMPANY, OF NEW YORK, N. Y., A CORPORATION OF ILLINOIS.

PROGRESSIVELY-MOVABLE ELECTRIC SWITCH AND CONTROLLING MECHANISM THEREFOR.

1,164,271.

Specification of Letters Patent. Patented Dec. 14, 1915.

Application filed January 2, 1908. Serial No. 408,872.

To all whom it may concern:

Be it known that I, BERT G. DUNHAM, of Rochester, in the county of Monroe and State of New York, have invented certain new and useful Improvements in Progressively-Movable Electric Switches and Controlling Mechanism Therefor; and I do hereby declare the following to be a full, clear, and exact description of the same, reference being had to the accompanying drawings, forming a part of the specification and to the reference-numerals marked thereon.

My present invention relates to electric switches and has for its primary object to provide an improved means for controlling the operation thereof, whereby the movable elements or wipers of a switch may be advanced progressively, arrested in the desired position of adjustment and restored to their normal position, said functions being performed automatically in conjunction with the other instruments or a system of instruments with which the switching mechanism may be employed.

To these and other ends the invention consists in certain improvements and combinations of parts all as will be hereinafter more fully described, the novel features being pointed out in the claims at the end of the specification.

In the drawings: Figures 1 and 2 are diagrammatic views illustrating the essential portions of a switching mechanism and operating devices therefor constructed in accordance with my invention. Fig. 3 is a plan view illustrating the mechanical construction of the switch. Fig. 4 is a detail sectional view taken on the line 4[—]4^x of Fig. 3. Fig. 5 is a similar view taken on the line 5[—]5^x of Fig. 2. Figs. 6 and 7 are detail views of pawl and detent.

Similar reference numerals in the several figures indicate similar parts.

In the illustrations I have shown a switching mechanism embodying my invention, arranged to perform the function of a finder switch for an automatic telephone system operating on the principle of central energy, in which use it serves to connect different telephone instrument circuits or one of several such circuits with another instrument, for instance, another switch or group of switches for performing additional opera-

tions. To this end the controlling mechanism comprises electromagnetic devices which operate conjointly to start the movable parts of the switch when an instrument circuit is closed and continue their progressive movement automatically until the terminals of such circuit are engaged, at which time said parts are arrested and retained in adjusted position until the instrument circuit is destroyed, when they are returned to their normal position in readiness for a subsequent operation.

My invention comprehends an association of parts which shall coöperate to enable the various functions of the apparatus to be carried out over complete metallic circuits, as distinguished from circuits in which ground or earth connections are employed in conjunction with one or both sides of the instrument circuit for effecting the movements of the adjustable parts of the switch. For convenience in illustration, as well as to facilitate tracing the various circuits, to which mention will be made hereinafter, these are shown supplied with current from different sources or batteries and conventional ground connections have been shown, but it will be understood that the several circuits are provided with current from a main battery or source of current supply and that said grounds indicate the return path or wire connected to the main battery.

In illustrating the preferred embodiment of my invention, I have shown a switch of the step-by-step type comprising generally a progressively movable member 1 which is adapted to be advanced progressively and to this end is made circular in form and is mounted upon a revoluble shaft 2 journaled at its lower end in a base plate 3 and supported at its upper end by a set screw 4, carried in a bracket 5, the ends of which extend downwardly and are secured to the base plate, as shown in Fig. 4. Carried on the movable element and insulated therefrom are contact springs or wipers 6, 7 and 8, arranged one below the other, the outer ends of which are adapted to coöperate with a series of insulated terminal contacts 9, 10 and 11, arranged in sets, those of each set being located in vertical alinement. The corresponding terminals of the several sets are supported in horizontal alinement upon a

segmental bridge 12 arranged concentric to the center of movement of the wipers and mounted upon the portion 3^a of the base comprising the cross bar and the side legs, 5 as shown, which latter are provided with parallel inner faces forming guides, between which one end of the base portion 3 is received. These faces are provided with V-shaped grooves receiving correspondingly 10 shaped ways, on the part 3, a construction which insures the accurate alignment of the two parts of the base both horizontally and vertically and permits the wipers to be accurately positioned in relation to their respective rows of contacts when the supports 15 for these parts are brought together.

The rear ends of the contact elements or wipers are provided with segments 6^a, 7^a and 8^a, with which coöperate brushes 15, 16 20 and 17 supported in the holder 18, of insulating material, secured to one of the ends of the bracket 5. Connected to the lower end of the shaft 2 is a coil spring 19, arranged in a casing 20 to which its outer end 25 is attached, the tension applied to the spring being sufficient to return the shaft and the parts supported thereon to the normal position, shown in Fig. 2, when they are released.

30 The means for rotating the movable contact elements comprise a leaf spring 21, supported on the upper end of an arm 22, having sufficient tension to normally engage the teeth or serrations 23 on the periphery of 35 the member 1 and forming a pawl for driving the latter. The arm 22 is pivoted at the point 24 and is provided with a laterally extending end 25 forming an armature which coöperates with the motor magnet 26

40 employed for actuating the operating devices. Also carried on the arm is a stud 22^a against which bears the end of the spring 22^b tending to move the arm in a direction to advance the member 1 and move the 45 armature 25 into retracted position when the motor magnet is deenergized. The locking device consists of a leaf spring detent 27 normally engaging the teeth 23, which is arranged beneath the spring pawl 21 and is 50 supported on the base 3 by a clip plate 28 adjustably secured by screws 29 in such position that when the pawl 21 is moved laterally out of engagement with the teeth 23 it will engage the detent 27 and cause it to be 55 also moved into an inoperative position. The means for releasing the movable element comprises a spring latch member or trip 30 having an end 31 which is adapted to hook over the end of the spring pawl 21.

60 At its lower end the trip 30 is attached to an armature 32, pivoted at 33 in proximity to the release magnet 34 by which it is actuated. Attached to the armature and extending upwardly from the pivot is an arm 35, 65 carrying at its end a pin 36 with which co-

operates the leaf spring 37 which is adapted to oscillate the arm to retract the armature 32. Supported on the base plate 3 in front of the latch 30 is a stud 38 which is rotatably adjustable on a binding screw 39 and 70 is adapted to coöperate with the spring to limit its lateral movement when the armature to which it is connected is retracted. This stud is arranged in such a position that the hooked end of the latch arm 30 is permitted when it is moved upwardly, to engage the end of lip of the pawl 21 and to retain its engagement therewith when retracted to hold the pawl and detent 27 in an inoperative position. From this arrangement of the parts it will be seen that the pawl 21 is always disengaged from the ratchet wheel or element 1 when the latter is in its normal position, and that as the latch arm or trip 30 is prevented from moving laterally toward the pawl, by the stud 38, the pawl will be disengaged therefrom to release the detent and these parts will be permitted to snap into engagement with the member 1 whenever the motor magnet 26 is 90 energized.

The movable member controls two circuits, which will be described in connection with the diagrammatic illustrations, which are formed by a contact spring 45 playing between insulated contact members 46 and 47 supported by a holder 48 on the base plate 3. The spring 45 has a normal tendency to engage the contact 46, but is held in engagement with the contact 47, when the movable member is in its normal position, by a pin 49 mounted on the latter which releases said spring upon the first step or movement of said member.

The switch and the mechanism controlling it may be used for purposes other than the one mentioned, but as it is especially adapted for use in connection with automatic telephone systems its use will be described in connection therewith, the operation thereof, 105 illustrated in Figs. 1 and 2, showing the manner in which any one of a plurality of instrument circuits may be connected with a single instrument circuit. Two of the contacts of each set of terminals, such as 9 and 10, are devoted to the line wires or conductors of instrument circuits, while the third one 11 forms the terminal of a branch operating or holding circuit, there being one of these branches for each instrument circuit 115 which serve successively to complete a circuit of the relays controlling the motor magnet to cause the successive operation thereof to advance the wipers. In Fig. 3 the switch is shown provided with a bank of contacts 120 containing fifty sets of terminals affording circuit connections for an equal number of instruments, but in Fig. 2 I have merely illustrated the contact bank as composed of four sets with the circuit connections for 130

four instruments, indicated by A, B, C and D leading therefrom, only two of which are shown complete and as said circuits are similar, a description of one will suffice for 5 all. In Fig. 2 instrument A is shown connected by the line wires A¹ and A² which lead respectively to the contacts 9^a and 10^a, corresponding to the fourth set in Fig. 3, with which the wipers 6 and 7 coöperate. 10 The remaining instrument circuits B, C and D, it will be understood, are similarly connected respectively with the third, second and first set of terminals. Bridged across the line wires of each circuit at the central 15 office, or exchange, are relays such as A³, which have two windings, one for each side of the line, connected in tandem to balance the line, their extremities being connected to the wires A', A² by the wires a', a², and to 20 the source of current supply represented by battery Z, whereby each of them will be energized when its respective instrument circuit is closed. The subscriber's instrument included in this circuit comprises the usual 25 transmitter T, receiver R and the normally open hook contacts A⁴.

The operating or holding circuit branches 30 corresponding to each instrument circuit, indicated by A⁵, B⁵, C⁵, D⁵, lead respectively from the terminals 11^a, 11^b, 11^c and 11^d to back contacts a, b, c and d of armatures a⁵, b⁵, c⁵ and d⁵ of the several line relays which are shown as grounded at z⁵ and coöperating with forward contacts, such as a⁴, which are 35 multiple terminals of the starter or booster wire A⁶ leading to the spring contact 45, the function of said wire being to supply the impulse of current necessary to start the operation of the switching mechanism, as will be 40 described more fully hereinafter.

In Fig. 1 the mechanism employed for controlling the operation of the movable contact elements of the switch is shown diagrammatically, said mechanism comprising 45 generally the motor magnet 26 and two relays associated therewith which may be termed controlling and arresting relays, which operate conjointly to cause the motor magnet to be energized and deenergized successively in unison with one of them and 50 finally arrested in the desired adjusted position when it is rendered inactive until the movable contact elements or wipers have been restored to their normal position. The 55 last mentioned operation is effected by means of the release magnet 34 which is provided with a circuit controlled by additional relays to which specific mention will be made more fully hereinafter.

60 The controlling relay, indicated by O, and the arresting relay, indicated by S, are arranged in a normally open starting circuit which is supplied with current by the booster wire when one of its several terminals is closed to operate the relays simulta-

neously, the controlling relay O supplying the initial impulse of current to start the motor magnet and the arresting relay S closing the operating or holding circuit for the two relays, whereby additional impulses 70 of current may be transmitted to the motor magnet to cause it to advance the movable contacts or wipers on the member 1 one or more steps. For this reason one end of the coil of the arresting relay S is attached to the 75 back contact 47 by a wire s, the other end thereof leading to the battery Z². On the motor magnet 26 is an armature o connected by the wire o' to the wire s, and normally coöperating with a back contact o² joined 80 by the wire o³ to one end of the coil of the controlling relay O which is supplied by current from the battery Z²⁰. It will thus be seen that when the circuit of an instrument, such as A, is closed, and the line relay, such as A³, thereof is energized, its armature a⁵ will be attracted and the movable contact elements or wipers of the switch being in the normal position, the following 85 circuits will be completed: ground z⁵, armature a⁵, contact a⁴, booster wire A⁶, spring contact arm 45, contact 47, wire s, relay S, battery Z², and wire o', armature o, contact o², wire o³, relay O, battery Z²⁰. This energizes both the relays S and O. The energizing 90 of the controlling relay O closes the armature o⁴, into engagement with the forward contact o⁵, grounded at z³, and as said armature is connected by the wire o⁶ to the coil of the motor magnet 26 which receives 95 current from the battery Z², the motor magnet will attract its armature o to interrupt the current in the circuit of the controlling relay O, which in turn will release the armature o⁴. This starting impulse of current 100 in the circuit of the motor magnet advances the member 1 a single step, causing the wipers thereon to engage the first set of terminals in the bank, whereupon the booster or starting circuit is broken by the spring contact 45 and current is supplied over the operating or holding circuit, which retains the relays in energized condition until the 105 contact elements have been advanced to pick up the terminals of a calling or closed instrument circuit. The contact 47 remains closed until the wipers contact with the first set of terminals in the bank, and as the wipers move from one set of terminals to the next, they make contact with the terminals they 110 are advancing to before breaking contact with the terminals they are leaving. Consequently the relay S will be held in an operative position, after its initial energization, until the wipers reach the terminals of 115 the calling line.

The third wiper 8 is connected by the wire s' to the armature s², which is actuated by the relay S into engagement with the forward contact s³ connected to the wire s,

so that as said wiper engages the terminal 11^a (Fig. 2) an impulse of current will traverse the following path: ground z^2 , armature d^3 , contact d , branch D^5 , terminal 11^a, wiper 8, (Fig. 2) thence by wire s' , armature s^2 , contact s^3 , relay S , battery Z^2 and wires s , o' , armature o , contact o^2 , wire o^3 , relay O , battery Z^{20} (Fig. 1). The energizing of the relay S closes the set of contacts s^2 , s^3 and energizes relay O which closes the motor magnet circuit at the contacts o^4 , o^5 . The impulse of current actuates the motor magnet which in turn opens the circuit of the controlling relay at the contacts o , o^2 , causing the controlling relay O to be de-energized with the consequent de-energization of the motor magnet, which allows the motor spring 22^b to advance the wipers into engagement with the second set of terminals. Thus it will be seen that the last mentioned circuits will be energized each time the wiper 8 engages a closed branch operating or holding circuit terminal and that the wipers will be arrested when the terminal of an open branch, such as A^5 , is picked up, at which time the wipers 6 and 7 will be in register with the terminals 9^a and 10^a of the subscriber's instrument circuit on which a call was initiated by the act of closing the line wires A' , A^2 .

For the purpose of illustrating the operation of the switching mechanism in one of the simplest uses to which it may be put, it has been shown as employed for connecting a plurality of instrument circuits with a single circuit which, for convenience in description, will be termed the called line. The latter is tied to the brushes 6 and 7 and comprises the wires E' , E^2 which lead 40 through normally closed contacts, on the magnet P , represented by armatures e' , e^2 , cooperating with back contacts e^3 , e^4 , from which the line wires E^{11} and E^{21} extend. Bridging the latter is a line relay E connected thereto by wires e^{11} , e^{21} , current being supplied thereto by the battery Z^4 for the purpose of attracting an armature e to open the release circuit of the switch and prevent the restoring of the wipers thereof, while the selected calling line is closed. It has been stated that the extended circuit may be used for connecting a calling circuit with other devices, such as another switch or a group of switches for performing additional operations incidental to the connecting of the extended circuit with the circuit of some particular instrument which it is desired to call, such as would be required in exchanges of any magnitude. However, in the present instance in order to describe the complete operation of the mechanism, I have shown the connection of a telephone instrument circuit with the wires E^{11} , E^{21} , comprising the line wires F' , F^2 across which are bridged the coils of a balancing relay F^2

to which current is supplied from the battery Z^5 . The complete circuit above outlined, may be traced as follows, from the calling subscriber's station A^3 to the called subscriber's station F : wire A' , contact 9^a , wiper 6, wire E' , armature e' , contact e^3 , wires E^{11} , F' , instrument F (not shown), wires F^2 , E^{21} , contact e^4 , armature e^2 , wire E^{12} , wiper 7, terminal 10^a, wire A^2 , instrument A . To this circuit current for talking purposes is supplied by the usual battery indicated conventionally by Z and Z^1 .

The release mechanism for restoring the parts of the switch to their normal position is normally incapable of operation but is designed to be rendered operative whenever the contact elements have been advanced and as soon as a cessation in the movement of the operating device occurs. This placing of the release mechanism in readiness to be operated may under certain circumstances effect the release, although these parts are so arranged that the release is controlled directly by the extended instrument circuit and the magnet 34 is prevented from operation during the time a selected instrument circuit is retained in closed condition. This object is attained in the present embodiment of the invention by providing the release magnet with a circuit having two sets of contacts and arranging relays for operating the one relay being adapted to be energized when current is flowing in the extended instrument circuit for opening its set of contacts and the other being associated with the operating devices and adapted to be energized to close its set of contacts and hold them closed while the contact elements of the switch are off normal.

One end of the coil of the release magnet 34 is connected by the wire f to the armature r on the relay R which cooperates with the back contact r' from which the wire f' extends to the armature e of the relay E bridged to the extended line, said armature normally engaging a back contact e^3 grounded at z^7 . The other extremity of the magnet 34 is connected by the wire f^2 to a back contact l of the armature L' connected to battery Z^7 . The release relay R is arranged in a circuit comprising a battery Z^6 to which one extremity of its coil is connected, the other end thereof being extended by the wire r^2 to the armature s^4 on the switching relay S , which normally engages a back contact s^5 forming a terminal of a wire r^4 connected to the booster or starting circuit A^8 , whereby the release relay may be energized when the spring contact arm 45 engages the forward contact 46, which occurs whenever the movable parts of the switch are adjusted out of their normal position which gives the following circuit: ground z^6 , contact 46, spring arm 45, wires A^3 , r^4 , contact s^5 , armature s^4 , wire r^2 , re-

lease relay R, battery Z^s . The energizing of the last mentioned relay closes the armature r into engagement with the contact r' , but as the switching relay S is energized 5 during the progressive movement of the switch wipers, the circuit of relay R is opened by the armature s^4 during the progressive movement of the switch. It will be remembered that the moment the wipers 10 and 7 are arrested they engage the terminals of a closed instrument circuit, such as 9^a, and 10^a, and the extended line is supplied with current energizing the relay E with the consequent result that when the armature s^4 is turned loose, the armature e of relay E is attracted, hence the normally closed contacts (e , e^5) in the release circuit are opened before the normally open contacts (r , r') are closed by the release relay R 15 which latter is energized when the switching relay S is deenergized. It will be seen, therefore, that the release circuit is rendered inoperative during the time the line, extended through the switch wipers, is energized 20 but that when the current is removed from the line the armature e is released and current is permitted to traverse the following path: ground z^s , contact e^5 , armature e , wire f , contacts r and r' , wire f , release magnet 34, wire f^2 , contact l , armature l' , battery Z^s .

The actuation of the release magnet attracts its armature 32, and sets the trip 30 in operative position and in order to de- 35 energize said magnet, to permit the spring 37 to retract the trip, the third set of contacts l , l' are arranged in the release magnet circuit and a relay L is employed for operating said contacts. This relay is 40 adapted to be energized upon the actuation of the release magnet and to be held up or retained in energized condition until the switch wipers have returned to their original position. To accomplish this object the relay L is first energized by a 45 starting circuit and current is retained in the relay during the return movement of the switch wipers by a holding circuit, which latter comprises the armature l^2 , arranged in that portion of the circuit of the 50 wire A^s which is attached to the spring 45, said armature being adapted to coöperate with the forward contact or terminal l^3 of the wire l^4 leading to the back contact o^1 of the armature o^3 on the operating relay O and extending therefrom over the wire l^5 which is connected to one end of the coil of the relay L, the other extremity thereof receiving current from the battery Z^s . The 55 starting circuit comprises the wire l^6 , joined to the wire l^5 , which terminates in the forward contact l^7 of the armature l^8 arranged on the release magnet 34 and grounded as indicated at z^s . The attraction of the last mentioned armature closes the following circuit:

ground z^s , armature l^8 , contact l^7 , wire l^8 , relay L, battery Z^s , which causes the armatures l^8 and l^9 to pull up, the former opening the release magnet circuit and the latter closing the following circuit, which retains current 70 in the locking relay L until the member l of the switch has been restored to its normal position: ground z^s , contact 46, spring 45, wire A^s , armature l^9 , contact l^9 , wire l^9 , contact o^1 , armature o^3 , wire l^5 , relay L, battery Z^s . The application of the holding circuit to the locking relay L enables it to hold the release circuit open and retain current in the relay P to retain the extended line in open condition during the retrograde movement of the wipers which prevents armatures e^1 , e^2 and l^9 from buzzing and removes possible disturbances from their respective lines. The armature o^3 is arranged in the last mentioned circuit to insure the relay L 80 releasing its armatures and to serve as a test to determine that the release circuit is restored after each operation, so that in the event said relay should be sluggish in its operation it could not hold over if the switch 85 should commence a second excursion immediately, as might occur if an instrument circuit happened to be closed during the retrograde movement of the wipers and the adjustment of the parts was such that a clear 90 break due to their speed of movement, did not take place between the spring 45 and the contact 46. When a switch of this character is employed as a finder switch for telephone 95 systems, a plurality of them is employed in groups and the corresponding terminals on the several switches are connected in multiple and said groups are associated with other switches termed selectors and connectors, the operation of which is effected over 100 the line extended by one of the finder switches, as represented by the wires E' , E'' , and E^3 and E^{21} . It is essential, therefore, that the extended line should be open during the operation of a finder switch, both 105 when its brushes are being advanced and restored, relay P therefore is provided with a divided circuit, the branches of which are controlled by each of the relays S and L, so 110 that it is energized to open the extended line during the movement of the switch wipers in either direction. This circuit consists of the battery Z^s , the wire p , from which lead the branches p' and p^2 connected to the armatures s^8 and l^9 on the relays S and L respectively, said armatures coöperating with 115 forward contacts s^7 and l^{10} grounded at z^s and z^{20} , one of these circuits being traceable over the following path: battery Z^s , wires p , p' , armature s^8 , contact s^7 , ground z^s , the 120 other path which the current may follow being: battery Z^s , wires p , p^2 , armature l^9 , contact l^{10} , ground z^{20} .

The controlling mechanism which I have described particularly adapts the device as 125

- a finder switch, as its operation in all respects is perfectly automatic. Starting as it does from normal position, it is capable of traversing a bank of contacts of any desired number by impulses of current received over normally closed branch holding circuits, said operation ceasing and the switch wipers being arrested when one of them picks up the terminal of an open branch. 5 The association of the switching and operating relays with the motor magnet in the manner described, permits the latter to be operated successively, while current is retained in the switching and operating relays by the successive impulses received as one of the wipers engages a closed operating circuit branch and the conjoint operation of these relays prevents their subsequently being energized after the movement of the 10 switch wipers has ceased, preventing any possible interference with a connection established by the subsequent closing of any other instrument circuit leading to the bank of switch contacts. This non-interference is due primarily to the fact that as soon as the member 1 has been actuated one step, the booster circuit is open and the impulses of current holding the relays in operative condition to continue the advancing movement of the member 1, are received over a different source, namely, the various branches of the holding circuit. Secondly, the actuation of the controlling relay O is necessary to energize the motor magnet and said relay 15 O in the first instance is actuated simultaneously with the switching relay S from current received over the booster line, but they thereafter receive additional impulses through a set of contacts (armature s^2 , contact s^3) which are retained in the closed position while the relay S is actuated, consequently when the latter fails to receive current and said contacts are permitted to open it thereupon becomes impossible to subsequently energize either the arresting relay or the controlling relay until the wipers of the switch have been returned to their normal position to restore the booster line in condition to be again energized. The release of the switch requires but a single impulse of current and the arrangement of the circuit of the release magnet is such that it cannot be influenced by stray currents during the operation of the motor driving devices and upon the completion of their operation is placed under the control of the selected instrument circuit to operate immediately upon the discontinuance of such circuit. 20 I claim as my invention:
1. In a switching mechanism, the combination with a plurality of terminals, a normally closed branch operating circuit leading from each terminal, a contact element coöperating with the terminals and mechanism for advancing it progressively, of a relay having a circuit which includes the contact element and by the latter is completed successively over the branch circuits, a motor magnet energized by the action of the relay for actuating the advancing mechanism, said magnet in turn controlling by its contacts the flow of current to said relay and means for imparting an initial impulse of current to the relay to advance the contact element into engagement with the first terminal. 25
  2. In a switching mechanism, the combination with a plurality of terminals, a movable contact element coöperating therewith and mechanism for advancing said element comprising a normally deenergized motor magnet, of a normally deenergized relay controlling the operation of said magnet, means for energizing said relay to cause a corresponding energization of the motor magnet to be effected and means operated when the motor magnet is energized for subsequently deenergizing said relay and by said relay effecting a corresponding deenergization of the motor magnet and means including said movable contact element for causing a continued operation of the motor magnet. 30
  3. In a switching mechanism, the combination with a plurality of terminals, branch circuits leading therefrom, a contact element coöperating with the terminals and mechanism for advancing it progressively, of a relay having a starting circuit and a holding circuit, the latter including the contact element and the circuit branches successively engaged thereby, a controlling relay adapted to be energized by the relay, a motor magnet for actuating the advancing mechanism adapted to be energized by the controlling relay, means for causing the controlling relay to be deenergized upon each advancement of the contact element, means for energizing the starting circuit to effect the initial movement of the relay and magnet and a source of current supply for said circuits. 35
  4. In a switching mechanism, the combination with a plurality of terminals, a movable contact element coöperating therewith and mechanism for advancing it progressively comprising a motor magnet, of electromagnetic mechanism for controlling the operation of the latter comprising two relays, one for controlling the magnet by imparting successive impulses of current thereto and the other for arresting the motor magnet by rendering the controlling relay inoperative and a source of current supply for said magnet and relays. 40
  5. In a switching mechanism, the combination with a plurality of terminals, normally closed branch circuits leading therefrom, a movable contact element coöperating 45

- with the terminals and mechanism for advancing it progressively comprising a motor magnet, of electromagnetic mechanism for controlling the operation of the magnet comprising a controlling relay which is adapted to be actuated upon each advancement of the contact element and an arresting relay for rendering the controlling relay inoperative, said motor magnet being arranged to be operated by the controlling relay, a starting circuit for supplying the initial impulse of current to both relays, a holding circuit for the arresting relay which includes the contact element and is supplied successively with current from the branch circuits until the element engages the terminal of a branch which has been opened, means for opening said branches and a source of current supply for said circuits.
6. In a switching mechanism, the combination with a plurality of terminals, normally closed branch circuits leading therefrom, a movable contact element coöperating with the terminals and mechanism for advancing it progressively comprising a motor magnet, of mechanism for controlling the magnet comprising a controlling relay and an arresting relay, a circuit for retaining the latter energized during the advancement of the contact element until it engages the terminal of an open branch circuit, a circuit for the controlling relay which is supplied with current when the arresting relay is energized and is provided with a set of contacts adapted to be open when the motor magnet is actuated, a circuit for said motor magnet which is energized by the controlling relay and a source of current supply for said magnet and relays.
7. In a switching mechanism, the combination with a plurality of terminals, normally closed branch circuits leading therefrom, a movable contact element coöperating with the terminals and mechanism for advancing it progressively comprising a motor magnet, of mechanism for controlling the magnet comprising a controlling relay and an arresting relay, a starting circuit for supplying an initial impulse of current to said relays and a holding circuit for the latter which receives current during the advancement of the contact element, said holding circuit having a set of open contacts which are adapted to be closed by the arresting relay and a set of closed contacts adapted to be opened when the motor magnet is energized, a motor magnet circuit which is closed when the controlling relay is energized and a source of current supply for said circuits.
8. In a switching mechanism, the combination with a plurality of terminals, normally closed holding circuit branches leading therefrom and a plurality of open starting circuit branches corresponding thereto, a contact element coöperating with the terminals and mechanism for advancing it progressively comprising a motor magnet, of two relays, a main starting circuit for energizing them which is common to the starting circuit branches, a main holding circuit for supplying current to said relays which is common to the holding circuit branches, sets of closed and open contacts in said holding circuit which are arranged to be opened and closed respectively by the energizing of one of said relays and the motor magnet, an open circuit for the motor magnet which is closed when the other relay is energized and a source of current supply for said circuits.
9. In a switching mechanism, the combination with a plurality of instrument circuits, terminals corresponding thereto and a normally closed holding circuit branch leading therefrom, a normally open starting circuit branch for each instrument circuit and means operated by each instrument circuit for reversing the condition of its corresponding holding and starting circuit branches, a movable contact element coöperating with the switch terminals and mechanism for operating it progressively comprising a motor magnet, of two relays, a main starting circuit for energizing them which is common to all the starting circuit branches, a main holding circuit which is also common to all the holding circuit branches and receives current as the contact element engages the terminal of closed branches, a set of contacts in the main holding circuit arranged on one relay which are closed when said relay is energized, a normally open circuit for the motor magnet having a set of contacts which are controlled by the other relay, a set of normally closed contacts located in the main holding circuit and arranged to be opened by the actuation of the motor magnet for the purpose of deenergizing the last mentioned relay to open the motor magnet circuit and a source of current supply for said circuits.
10. In a switching mechanism, the combination with a plurality of terminals, a contact element coöperating therewith, an electromagnetic device for moving it progressively and relays associated therewith and arranged to operate conjointly to impart impulses of current to the operating device to advance the contact element into the desired position of adjustment and thereupon render the further transmission of current impulses to the relays impossible, of a main starting circuit for imparting the initial impulse of current to said relays, said circuit being provided with a plurality of normally open branches which may be closed to energize said main circuit and a switch controlling the latter which is opened when the contact element is advanced out of its normal position to render the starting circuit inoperative.

11. The combination with a plurality of telephone instrument circuits, a switching mechanism having terminals therefor arranged in sets, a normally closed branch holding circuit leading to one terminal of each set and a contact element coöperating therewith, of electro-magnetic mechanism for operating it progressively, relays which operate conjointly to control said mechanism, a main starting circuit for the relays having normally open branches corresponding to the instrument circuits and means operated by each instrument circuit for reversing the condition of its respective starting and holding circuit branches, a main holding circuit for the relays which receives current over the closed holding circuit branches during the advancement of the contact element, a set of contacts in said circuit controlled by one of the relays for destroying the holding circuit when the contact element engages the terminal of an open branch thereof. 10
12. In a switching mechanism for picking up one of a plurality of instrument circuits and extending it, the combination with terminals for said circuits, a contact element coöperating therewith, mechanism for adjusting the element and a locking device coöperating therewith, of a magnet for releasing it, having a circuit provided with two sets of contacts controlled by two relays, one of said relays being adapted to be energized to close its contacts thereby completing the release circuit when the switching devices are moved out of their normal position, the other relay being adapted to be energized by current in the extended line to hold its set of contacts open to render the release circuit inoperative. 20
13. In a switching mechanism for selecting and extending one of a plurality of instrument circuits, the combination with terminals for said circuits, a contact element coöperating therewith, mechanism for adjusting the element and a locking device coöperating therewith, of a magnet for releasing the element having a circuit provided with sets of normally closed and normally open contacts, means operated when an instrument circuit is extended to open the closed set of contacts, a relay for closing the open set of contacts when the relay is energized having a circuit which is energized when the switch contact element is out of its normal position. 30
14. In a switching mechanism for selecting and extending one of a plurality of instrument circuits, the combination with terminals for said circuits, a contact element coöperating therewith, mechanism for operating the element and a locking device coöperating therewith, of a magnet for releasing the element, a circuit therefor, two relays controlling said circuit, one relay operating in conjunction with the switch operating mechanism to attract its armature thereby rendering the release circuit capable of conducting current when the switching mechanism is at rest, the other relay operating in conjunction with the extended instrument circuit for rendering the release circuit inoperative during the time the extended circuit is maintained. 40
15. The combination with a plurality of instrument circuits, and a switch for selecting one or another of said circuits comprising terminals for the latter, a contact element coöperating therewith and devices for operating the contact element and securing it in adjusted position, of a trip for releasing said element, a magnet for actuating the trip into operative position, means for energizing the magnet controlled by the instrument circuit and a relay actuated when said magnet is energized for subsequently deenergizing it. 50
16. In a switching mechanism for selecting one of a plurality of instrument circuits and extending such selected line comprising a plurality of line terminals and a contact element coöperating therewith, the combination with devices for operating said element in one direction and restoring it, and a locking device for holding the element in adjusted position, of a trip coöperating therewith, a magnet for setting the trip in operative position and a circuit for the magnet, means adapted to be controlled by the selected instrument circuit for effecting the energization of the magnet, and a relay for subsequently causing its deenergization and rendering its circuit inoperative during the retrograde movement of the contact element. 60
17. In a switching mechanism for selecting and extending one of a plurality of instrument circuits comprising a plurality of line terminals and a contact element coöperating therewith, the combination with means for advancing the element progressively and locking it in adjusted position, of a spring operated trip for unlocking the element, a magnet for actuating the trip into an operative position, a circuit for said magnet and a relay actuated by the magnet for controlling its circuit which causes the magnet to be deenergized immediately upon each energization. 70
18. In a switching mechanism for selecting and extending one of a plurality of instrument circuits comprising a plurality of line terminals and a contact element coöperating therewith, the combination with means for advancing the element progressively and locking it in adjusted position, of a spring operated trip for unlocking the element, a magnet for actuating the trip into an operative position having a circuit, a relay controlling the latter, a relay starting circuit which is closed by the operation of the mag. 80

- net and a holding circuit for the relay which is closed and retained closed while the contact element is moved out of its normal position and a device for returning the latter 5 when it is unlocked.
19. In a switching mechanism for selecting and extending one of a plurality of instrument circuits, the combination with a plurality of line terminals, a contact element 10 co-operating therewith, means for driving the element in one direction and means for locking it in adjusted position, of a trip for unlocking the element, a release magnet for setting the trip, having a circuit provided 15 with three sets of contacts, three relays controlling them which are arranged for conjoint operation, one relay being adapted to close one set of contacts and render the circuit in condition to be energized whenever 20 the contact element is moved out of its normal position, the second relay being adapted to open another set of contacts to prevent the energizing of the circuit while the extended instrument circuit is energized and the third 25 relay being arranged to open the third set of contacts after the release magnet has been energized, means for actuating the trip after it has been set and means for restoring the contact element to normal position.
20. In a switching mechanism for selecting and extending one of a plurality of instrument circuits, the combination with a plurality of line terminals, a contact element 30 co-operating therewith, electromagnetic devices for driving it in one direction, a locking device for securing the element in adjusted position and means for restoring it, of a trip for disengaging the locking device, a magnet for setting the trip in operative 35 position and means for operating it, a circuit for said magnet having two sets of contacts and two relays controlling them, one relay being associated with the electromagnetic operating devices and adapted to close one 40 set of contacts when energized upon the cessation of movement of the contact element, and the other relay being adapted to be energized by current flowing in the extended instrument circuit to open the other set of contacts.
21. In a switching mechanism for selecting and extending one of a plurality of instrument circuits, the combination with a plurality of line terminals, a contact element 45 co-operating therewith and devices for operating the element in one direction, a device for securing the element in adjusted position, means for restoring the element and a trip for disengaging the securing device, of 50 a magnet for actuating the trip, a circuit for said magnet having a normally closed and a normally open set of contacts, a relay adapted to be energized by current in the extended instrument circuit for opening the closed set of contacts, another relay adapted to be en-
- ergized to close the open set of contacts when the contact element is at rest in an adjusted position, said relay being under the control of the operating devices and prevented from operation during the advancing movement 70 of the contact element.
22. In a switching mechanism for selecting and extending one of a plurality of instrument circuits, the combination with a plurality of line terminals, a contact element 75 co-operating therewith and a spring for rotating it in one direction into its normal position, a switch which is opened when the element is in its normal position, and electromagnetic operating devices for automatically advancing the element in the other direction, a device for locking the latter in adjusted position and a spring operated trip for unlocking it, of a release magnet for setting the trip having a circuit provided 80 with three sets of contacts, and three relays for controlling them, one relay being adapted to open one set of contacts and to be energized by current in the extended instrument circuit, the second relay being adapted 85 to close another set of contacts and the third relay being adapted to open the third set of contacts, the second and third relays having circuits which include the switch and are closed by it when the contact element is 90 out of its normal position.
23. In a switching mechanism for selecting and extending one of a plurality of instrument circuits, the combination with a plurality of line terminals, a contact element 100 co-operating therewith, a spring for rotating it in one direction into its normal position and a spring switch which is opened when the element is in its normal position, electromagnetic operating devices for automatically advancing the element in the other direction, a device for locking the latter in adjusted position and a spring operated trip for unlocking it, of a release magnet for setting the trip, having circuit adapted to be 105 energized when current is removed from the extended instrument circuit and having a set of normally closed contacts, of a relay controlling the latter having a starting circuit which is energized when the release mag- 110 net is energized and also provided with an open holding circuit which includes the spring switch and has a set of open contacts closed by the relay itself, said holding circuit serving to retain the relay in energized 115 condition to hold the release circuit open while the contact element is out of its normal position.
24. The combination with a plurality of normally open instrument circuits, terminals therefor, contact elements co-operating therewith and conductors for extending said circuits leading therefrom, of electromagnetic operating devices under the control of said circuits and adapted to be actuated 120
- 125
- 130

when one of them is closed for automatically advancing the contact elements and arresting them in engagement with the terminals of said closed instrument circuit, 5 means for locking the elements in adjusted position and means for restoring them to their normal position, a trip for disengaging the locking devices, a release magnet for actuating the trip provided with a circuit 10 having two sets of contacts, a relay arranged in the extended instrument circuit which operates to open one set of contacts and render the release circuit inoperative while the extended circuit is energized, another relay 15 for closing the other set of contacts which is normally inoperative and is rendered operative upon cessation of movement of the electromagnetic operating devices.

25. The combination with a plurality of 20 normally open instrument circuits, terminals therefor, a contact element coöperating therewith and normally inoperative electromagnetic devices for operating it automatically, of a booster circuit for supplying the 25 initial impulse of current for starting said devices, means operated upon the closing of an instrument circuit for energizing the booster circuit, a device for locking the contact element in adjusted position, a magnet 30 for releasing it having a circuit which is adapted to be energized upon the opening of a previously closed selected instrument circuit, a relay, said relay having sets of contacts included in the booster circuit and 35 release magnet circuit, said relay being adapted to be energized to open said sets of contacts upon the transmission of an impulse of current to said release magnet and means for maintaining current in said relay until 40 the contact element has returned to its normal position.

26. In a finder switch mechanism the combination with a plurality of line terminals, 45 normally open instrument circuits leading to the latter, a movable contact element coöperating therewith, electromagnetic devices for operating the element automatically upon the closing of an instrument circuit and a device for locking the element in adjusted position, 50 of a trip for disengaging the locking device, a magnet for operating the trip having a circuit adapted to be energized upon the opening of a previously closed selected instrument circuit, a relay for initially opening 55 said magnet circuit, a circuit controlling said relay which is energized when the release magnet is energized, said relay circuit having a set of normally closed contacts which are opened during the movement of 60 the electromagnetic operating devices.

27. In a switching mechanism for selecting and extending one of a plurality of instrument circuits comprising terminals therefor and a contact element coöperating

therewith, the combination with a conductor 65 extending from the element having normally closed contacts therein, means for advancing the elements, a set of switch contacts which are closed when the element is out of its normal position and devices for 70 restoring the latter, of a relay for opening the conductor contacts having a normally open circuit, a second relay for closing said circuit which is actuated by the restoring devices, and a holding circuit for the second 75 relay which is controlled by the switch contacts and retains its relay in energized condition during the retrograde movement of the contact element.

28. In a switching mechanism the combination with a plurality of normally open instrument circuits each comprising two line wires, terminals for said wires arranged in sets and separate contact elements adapted to coöperate with the corresponding terminals of the several sets, and conductors leading from the elements, of electromagnetic operating devices adapted to be actuated by the closing of an instrument circuit to advance the elements into engagement with the 90 terminals of said closed instrument circuits, of devices for restoring the elements to their normal position comprising a release magnet having a circuit provided with a set of normally closed contacts, a relay bridged to the 95 conductors and opening said contacts when the conductors are supplied with current from the connected instrument circuit and a relay energized when the elements engage the terminals of said instrument circuit to 100 close a second contact in said release magnet circuit.

29. In a switching mechanism, the combination with a plurality of full metallic instrument circuits which are normally open, 105 a normally open branch starting circuit and a normally closed branch holding circuit for each instrument circuit and means operated when the instrument circuits are closed for reversing the condition of their respective 110 branch circuits, terminals for the line wires of each instrument circuit and its holding circuit branch, said terminals being arranged in sets, separate contact elements arranged to coöperate with the corresponding terminals of the several sets, circuit conductors leading from two of the elements and a movable member supporting the latter, of devices for advancing the member in one direction comprising a motor magnet and means 115 for moving it in the opposite direction, of relays controlling the operation of the motor magnet having a starting circuit adapted to receive an initial impulse of current transmitted over the starting circuit branch of a 120 closed instrument circuit and also provided with a holding circuit to which current is supplied successively by the closed holding 125

circuit branches, restoring devices for releasing the member comprising a release magnet adapted to be rendered inoperative when the circuit conductors are connected to a closed instrument circuit and to be actuated when said instrument circuit is destroyed.

30. In an automatic telephone system, the combination of a calling and a called subscriber's station, and automatic switching mechanisms for connecting such substations, one or more of such mechanisms comprising a relay and a motor magnet each adapted upon the removal of the receiver at the subscriber's station to repeatedly energize and deenergize the other to operate such mechanism, and a second relay controlling contacts in the circuit of the first relay.

31. An automatic switching mechanism comprising the combination of contacts and selecting wipers, a relay and a motor magnet each adapted to repeatedly energize and deenergize the other to operate such mechanism, the number of energizations depending upon the electrical condition of said contacts and a second relay having contacts in the circuit of the coil of said first relay.

32. In an automatic telephone system, the combination of a calling and a called subscriber's station, automatic switching mechanisms for connecting such substations, one or more of such mechanisms comprising selecting switches, a relay and a motor magnet each adapted upon the removal of the receiver at the subscriber's station to repeatedly close and open a local circuit of the other to operate such mechanism, the rate of energization and deenergization of the relay depending

upon the natural period of operation of the motor magnet.

33. In an automatic telephone system, the combination with a selector switch, of a relay and a motor magnet therefor, said relay controlling a pair of normally open contacts in the circuit of the motor magnet, said motor magnet controlling a pair of normally closed contacts in the circuit of the relay, the circuit of said relay being normally open at another point, a line relay at the central office individual to the subscriber's line having contacts adapted to close the circuit of the first relay at the latter point whereby a vibratory action will occur between the first relay and the motor magnet, and mechanism adapted to be advanced step-by-step by the operation of the motor magnet.

34. In an automatic telephone system, the combination with a selector switch having stationary contacts and selecting wipers, of a relay and a motor magnet therefor, a pair of normally open contacts controlled by said relay, the circuit of said motor magnet being controlled by the contacts of said relay, a pair of normally closed contacts for said motor magnet, adapted when opened to sever the circuit through said relay whereby the circuit of said motor magnet is interrupted, a second relay having contacts in the circuit of the first and having a circuit of its coil completed through the stationary contacts and the selecting wipers of said selector switch.
